UNITED STATES PATENT OFFICE

ARTHUR L. CORNWELL, OF WELLSVILLE, NEW YORK

WHEEL PULLER

Application filed May 1, 1931. Serial No. 534,202.

This invention relates to wheel pullers which are adapted to be applied to the hub portions of vehicle wheels or the like and to withdraw the wheels from their axles, and the invention relates more especially to that type of puller which comprises an adaptor for threading onto the wheel hub and a puller member for engaging the adaptor and carrying a pressure-producing member for engaging the end of the axle to force the wheel therefrom. The primary object of my invention is to provide an improved puller of this type which is more compact and easier and faster to use than like pullers heretofore known.

Each wheel puller of this type ordinarily comprises several adaptors for fitting different wheels and one puller member which will fit all the adaptors. Heretofore this puller member has ordinarily comprised two or more pieces which need to be disassembled and assembled at each wheel pulling operation or at least when changing adaptors. My invention herein embodies a puller member which permanently remains in its assembled relation and is adapted to be instantly engaged with and disengaged from the adaptors, thereby providing quick operation and eliminating the great amount of time heretofore required in wheel pulling. The production of such an improved puller comprises another object of my invention.

My improved puller comprises one or more adaptors and a puller member, the latter comprising a body member having a plurality of segmental elements therein for engaging the adaptor. The construction is such that when the adaptor has been threaded onto the wheel hub the body member can be instantly snapped thereover and the wheel immediately pulled thereafter. The puller member furthermore comprises means whereby the adaptor can be instantly released and removed therefrom after the wheel has been withdrawn, this means functioning to move the segmental elements into adaptor-engaging or disengaging positions. The production of such a puller embodying these improved functions comprises a further object of my invention.

While I have herein for convenience and clearness of description referred to my invention as a wheel puller, I desire it to be clearly understood that I am aware that the invention has other equivalent applications, such as the pulling of gears, bushings, etc., and I intend that all such equivalent uses shall be considered as coming within the scope of the invention as defined herein.

With the above and other objects in view, as will become more apparent as this description proceeds, my invention consists in the features of construction and operation set forth in the following description and illustrated in the accompanying drawings. In such drawings I have shown one specific embodiment of my invention but it will be understood that the invention can be otherwise embodied and that the drawings are not to be construed as defining or limiting the scope of the invention, the claims appended hereto being relied upon for that purpose.

Referring to the figures of the drawings,

Fig. 1 is a longitudinal sectional view through my improved puller and showing the same in position to engage an adaptor on a wheel to be pulled;

Fig. 2 is a fragmentary sectional view thereof showing the puller being engaged with the adaptor;

Fig. 3 is a similar view showing the puller fully engaged with the adaptor;

Fig. 4 is a like view showing the puller being removed from the adaptor after the wheel has been loosened from the axle;

Fig. 5 is a front end view of the puller member shown in Fig. 1; and

Fig. 6 is a sectional view taken on line 6-6 of Fig. 1.

I will now proceed to describe the specific embodiment of my invention herein illustrated by reference to the wheel puller shown in the accompanying drawings. This puller comprises an adaptor 10 and a puller member 12, the latter including a body member 14, a plurality of adaptor-engaging elements 16, and a pressure-producing screw 18 threaded into a sleeve 20 carried by the body member. The adaptor is internally threaded to engage the threads of a wheel hub 22 and the body

member has a relatively large opening in its front end for receiving the adaptor, whereby the elements 16 can engage therewith for the pulling operation. The adaptor is preferably 5 of a contractible nature whereby coacting cam faces, hereinafter described, will cause a firm binding thereof onto the hub during pulling of a wheel. When the wheel has been pulled, the adaptor may be instantly released 10 from the elements 16 and I have mounted the sleeve 20 to slide in a manner to perform this function, all of which will now be more specifically described.

The member 14 is a hollow, shell-like body 15 open at its front end for receiving the adaptor 10 and the sleeve 20 is mounted for a limited sliding movement in a bore through the rear wall of this body. The sleeve projects into the chamber 24 of the member 14 and the elements 16 are supported thereon. I have illustrated the device as having six of these elements, all of which are identical and provided with segmental base portions 26 formed to fit the sleeve. Extending forwardly from each 20 such portion is an intermediate portion which terminates in a segmental forward portion 28 for engaging the adaptor within and the member 14 without. The adaptor 10 is internally threaded to engage a wheel hub 22, 25 is preferably split at 30 to render it contractible, and is provided with a shoulder 32 on its periphery. The forward portions 28 of the elements 16 are provided with internal shoulders 34 for engaging the shoulder 32 and also 30 with external beveled faces 36 for coacting with a like face 38 on the member 14 whereby to cause contraction of the adaptor upon relative rearward movement of the member 14.

The sleeve 20 has a rear portion 40 fitting 40 within the bore of member 14, an intermediate shouldered portion 42, and a forwardly-extending portion 44. The base portion 26 of each element 16 has forward and rearward segmental projections 46 and 48 which seat 45 against the sleeve 20, a spring coil 50 surrounding all the portions 26 between these projections and serving to hold the projections in contact with the sleeve. The projections 46 rest on the sleeve portion 44 and a 50 compression spring 52 between these projections and the shouldered sleeve portion 42 normally urges the elements forwardly to the position shown in Fig. 1. The projection 48 is V-shaped in cross section and the rear shoulder of the portion 42 is inclined to cooperate therewith for a purpose hereinafter described.

The parts of the puller member 12 are shown in their normal relation in Fig. 1, in 55 which relation the sleeve 20 is in its rearmost position and the spring 52 is acting to force the elements 16 forwardly into contact with the member 14 and, in cooperation with the coacting cam faces 36 and 38, is resiliently 60 holding the ends 28 in their innermost radial

position. The adaptor 10 having been threaded to proper position on the hub 22, the puller member is applied thereto merely by forcing the same over the adaptor, as shown in Figs. 2 and 3. The engaging of the ends 70 28 with the adaptor forces the elements 16 rearwardly and along the cam faces 38. When the shoulder 32 passes the shoulders 34, the elements snap into engagement with the adaptor, as shown in Fig. 3, the shoulders 75 32 and 34 being thereafter resiliently held in engagement, as will be understood. The operator now rotates the screw 18 by means of its handle 54, whereupon the inner end of the screw contacts with the end 56 of the axle and 80 forces the member 14 rearwardly. The cam faces 36-38 thereupon cause the adaptor 10 to contract into gripping engagement with the hub and the wheel to be withdrawn.

When the wheel has been withdrawn to a 85 sufficiently loose position, the adaptor is released from the puller merely by backing off the screw 18 and pushing the screw and sleeve inwardly. The effect of this inward movement of the sleeve is shown in Fig. 4, wherein the spring 52 has been compressed and the projections 48 have dropped from the portion 42 of the sleeve onto the relatively lower portion 40 thereof. This action has thrown the adaptor-engaging ends 28 of the elements 16 90 radially outward out of engagement with the adaptor, which is thereupon free to pass outward of the puller member. The puller is also locked in this open position and cannot be again used until placed in the closed position. To again place the puller in this closed and operative position, it is only necessary to pull the screw outwardly, whereupon the V shape of the projections 48 causes them to 100 be forced radially outward onto the larger 105 portion 42 of the sleeve. The spring 52 thereupon immediately forces the sleeve to its rearmost position and the parts assume the operative position of Fig. 1, wherein the holder is again ready for use.

It will, therefore, be seen that I have produced a new and improved pulling instrument which can be instantly attached to and removed from a cooperating adaptor in a manner rendering the instrument of particular advantage in the ease and speed of its operation.

Having thus described my invention, what I claim as new and desire to secure by Letters Patent is:

1. A wheel puller comprising an adaptor for engaging the hub of a wheel, a body member having an opening at its front end for receiving the adaptor therewith, means within the body member for engaging the adaptor and preventing its return outward movement through said opening, means carried by the body member for engaging an axle on which the engaged wheel is mounted and for forcing the member outwardly therefrom,

and means for causing outward movement of the first-named means in a substantial radial direction to permit removal of the adaptor through said opening.

5 2. A wheel puller comprising an adaptor for engaging the hub of a wheel, a body member having an opening at its front end for receiving the adaptor thereinto, means within the body member for engaging the adaptor and preventing its return outward movement, resilient means for urging the first-named means into engagement with the adaptor, means carried by the body member for engaging an axle on which the engaged 10 wheel is mounted and for forcing the member outwardly therefrom, and cooperating means whereby the first-named means can be released from the adaptor to permit removal of the adaptor from said opening.

20 3. A wheel puller comprising an adaptor for engaging the hub of a wheel, a body member having an opening at its front end for receiving the adaptor thereinto, means within the body member for engaging the adaptor and preventing its return outward movement, means including resilient means and coacting cam faces for urging the first-named means into engagement with the adaptor, means carried by the body member for engaging an 25 axle on which the engaged wheel is mounted and for forcing the member outwardly therefrom, and cooperating means whereby the first-named means can be released from the adaptor to permit removal of the adaptor from said opening.

4. A wheel puller comprising a contractible adaptor for engaging the hub of a wheel, a body member having an opening at its front end for receiving the adaptor thereto, means within the body member for engaging the adaptor and preventing its return outward movement through said opening, means carried by the body member for engaging an axle on which the engaged wheel is mounted 45 and for forcing the member outwardly therefrom, means providing coacting cam faces for causing the adaptor to be contracted onto the hub upon said outward movement, and means for releasing the first-named means 50 without relative rotation between the body member and adaptor to permit removal of the adaptor through said opening.

5. A wheel puller comprising a hollow body member, a plurality of segmental elements therein, a contractible collet having internal threads for engaging the hub of a wheel and adapted to be received within the forward portions of said elements, and means carried by the body member for engaging an 55 axle on which the engaged wheel is mounted and for forcing the member outwardly therefrom, said forward portions and the corresponding portions of the collet and body member having interengaging faces including beveled surfaces for causing contraction

of the collet onto the hub and withdrawing of the wheel from the axle upon said outward movement of the body member.

6. A wheel puller comprising a hollow body member, a plurality of segmental elements therein, a contractible collet having internal threads for engaging the hub of a wheel and adapted to be received within the forward portions of said elements, means mounting the elements for pivotal movement 70 into and out of engagement with the collet, and means carried by the body member for engaging an axle on which the engaged wheel is mounted and for forcing the member outwardly therefrom, said forward portions and the corresponding portions of the collet and body member having inter-engaging faces including beveled surfaces for causing contraction of the collet onto the hub and withdrawing of the wheel from the axle upon said outward movement of the body member.

7. A wheel puller comprising a hollow body member, a plurality of segmental elements therein, a contractible collet member having internal threads for engaging the hub of a wheel and adapted to be received within the forward portions of said elements, and means carried by the body member for engaging an axle on which the engaged wheel is mounted and for forcing the member outwardly therefrom, said forward portions being constructed to have a cam-like engagement with one of said members and a positive shouldered engagement with the other member for causing contraction of the collet 90 member onto the hub and withdrawing of the wheel from the axle upon said outward movement of the body member.

8. A wheel puller comprising a hollow body member, a plurality of segmental elements therein, the forward exterior edge portions of the elements and the corresponding internal wall of the body member having cooperating beveled faces adapted to cause contraction of the elements upon relative forward movement thereof, a contractible collet having internal threads for engaging the hub of a wheel, the segmental elements and collet having cooperating shoulders whereby the former may engage and prevent outward movement of the latter, and means carried by the body member for engaging an axle on which the engaged wheel is mounted and for forcing the member outwardly whereby to contract the collet onto the hub and withdraw the wheel from the axle.

9. A wheel puller comprising a hollow body member, a plurality of segmental elements therein, a contractible collet member having internal threads for engaging the hub of a wheel and adapted to be received within the forward portions of said elements, a power screw carried by the body member for engaging an axle on which the engaged 125

wheel is mounted and for forcing the body member outwardly therefrom, said forward portions being constructed to have a positive shouldered engagement with one of said members and a beveled surface engagement with the other member for causing contraction of the collet member onto the hub and withdrawing of the wheel from the axle upon said outward movement of the body member, and means carried by the body member for supporting the segmental elements and permitting a limited forward and rearward movement thereof axially of the screw.

10. A wheel puller comprising a hollow body member, a plurality of segmental elements therein, a contractible collet member having internal threads for engaging the hub of a wheel and adapted to be received within the forward portions of said elements, a power screw carried by the body member for engaging an axle on which the engaged wheel is mounted and for forcing the body member outwardly therefrom, said forward portions being constructed to have a positive shouldered engagement with one of said members and a beveled surface engagement with the other member for causing contraction of the collet onto the hub and withdrawing of the wheel from the axle upon said outward movement of the body member, means carried by the body member for supporting the segmental elements and permitting a limited forward and rearward movement thereof axially of the screw, and means for holding the said forward portions of the elements in a relatively spread relation when the elements are in a rearward position.

11. A wheel puller comprising a hollow body member, a plurality of segmental elements therein, a contractible collet member having internal threads for engaging the hub of a wheel and adapted to be received within the forward portions of said elements, a power screw carried by the body member for engaging an axle on which the engaged wheel is mounted and for forcing the body member outwardly therefrom, said forward portions being constructed to have a positive shouldered engagement with one of said members and a beveled surface engagement with the other member for causing contraction of the collet onto the hub and withdrawing of the wheel from the axle upon said outward movement of the body member, means carried by the body member for supporting the segmental elements and permitting a limited forward and rearward movement thereof axially of the screw, means for holding the said forward portions of the elements in a relatively spread relation when the elements are in a rearward position, and means normally forcing the elements forwardly into contact with the body member when said elements are forwardly of said rearward position.

12. A wheel puller comprising a hollow body member, a sleeve slidably mounted therein, a plurality of segmental elements supported on the sleeve within the member, a contractible collet having internal threads for engaging the hub of a wheel and adapted to be received within the forward portions of said elements, means extending through the sleeve for engaging an axle on which the engaged wheel is mounted and for forcing the member outwardly therefrom, said forward portions and the corresponding portions of the collet and body member having inter-engaging faces including beveled surfaces for causing contraction of the collet onto the hub and withdrawing of the wheel from the axle upon said outward movement of the body member, and means whereby the said forward portions of the elements are brought to a relatively spread relation when the sleeve is moved to a predetermined position.

13. A wheel puller comprising a hollow body member, a sleeve slidably mounted therein, a plurality of segmental elements supported on the sleeve within the member, resilient means holding the elements in contact with the sleeve, a contractible collet having internal threads for engaging the hub of a wheel and adapted to be received within the forward portions of said elements, means extending through the sleeve for engaging an axle on which the engaged wheel is mounted and for forcing the member outwardly therefrom, said forward portions and the corresponding portions of the collet and body member having inter-engaging faces including beveled surfaces for causing contraction of the collet onto the hub and withdrawing of the wheel from the axle upon said outward movement of the body member, said resilient means being adapted to bring the said forward portions of the elements to a relatively spread relation when the sleeve is moved to a predetermined position, and resilient means for forcing the elements forwardly into contact with the body member when the sleeve is moved to another position.

14. A wheel puller comprising a hollow body member, a sleeve slidably mounted therein, a plurality of segmental elements supported on the sleeve within the member, the forward exterior edge portions of the elements and the corresponding internal wall of the body member having cooperating beveled faces adapted to cause contraction of the elements upon relative forward movement thereof, a contractible collet having internal threads for engaging the hub of a wheel, the segmental elements and collet having cooperating shoulders whereby the former may engage and prevent outward movement of the latter, means for bringing the said forward portions of the

elements to a relatively spread relation when the sleeve is moved to a predetermined position and for drawing said portions into a relatively contracted relation when the
5 sleeve is moved to another position, resilient means for forcing the elements forwardly into contact with the body member when the sleeve is moved to the last-named position, and means extending through the sleeve
10 for engaging an axle on which the engaged wheel is mounted and for forcing the member outwardly therefrom.
